D. STUART.

Cooking Stove.

No. 25,451.

Patented Sept. 13, 1859.

UNITED STATES PATENT OFFICE.

DAVID STUART, OF PHILADELPHIA, PENNSYLVANIA.

COOKING-STOVE.

Specification of Letters Patent No. 25,451, dated September 13, 1859.

To all whom it may concern:

Be it known that I, DAVID STUART, of Philadelphia, in the county of Philadelphia and State of Pennsylvania, have invented 5 an Improvement in Gas-Consuming Cooking-Stoves, and that the following is a full, clear, and exact description of the principle or character which distinguishes it from all other things before known and of the 10 usual manner of making, modifying, and using the same, reference being had to the accompanying drawings, of which—

Figure 1 is a middle vertical section from front to back of the stove. Fig. 2 is a cross 15 section in the line $z z$ of Fig. 1. Fig. 3 is a bottom view showing the passages for heated air under the oven. Fig. 4 is an interior view of the grate front, and Fig. 5 is a front elevation of the grate front.

20 My invention is an improvement in gas consuming cooking stoves described and represented as follows:

For the purpose of heating the air on its 25 passage to the distributer a it enters aperture a' and is passed into and through the middle of the rear part of the hollow cross piece or bridge b , on the top of the stove and thence down through the divider m as clearly 30 shown in Figs. 1 and 2 and indicated by the black arrows. The distributer a is a narrow box extending across the stove and is furnished with numerous small apertures e along its front over the fire, one of which 35 apertures is shown in Fig. 1. From the middle of this box there rises an oval shaped neck or passage m which I call the divider (as it divides the draft at this point). Into 40 this neck the air enters from a descending neck piece n which proceeds from the lower wall s of the hollow crosspiece, and fits over the upper part of the piece m . When the hollow crosspiece b is in place on the stove, its side ends c , c , open into side passages

r , r , formed under the top plate x of the stove which communicate with openings u 45 in the side plates of the stove, and as the air escapes from the numerous small jets of the distributer it is highly heated and causes a perfect combustion of the unconsumed gases arising from the fire. 50

I am aware that the top plates or cross pieces or bridges of cooking stoves have been made hollow for the purpose of preventing their cracking and warping and to such a device I lay no claim. I merely claim the 55 use of the crosspiece as a vehicle for hot air to the distributer in the manner above set forth. This mode of supplying the hot air to the distributer enables me to use all the 60 heating surface of the grate front for supplying hot air to the under side of the oven which is an improvement on the mode set forth in my application now pending in the U. S. Patent Office according to which, one 65 half the grate front is used to heat air to go to the distributer and one half to the under part of the oven.

Figs. 1, 3, 4 and 5 show the arrangement for heating air and conveying it to the bottom of the oven. The air enters the grate 70 front at a^2 , a^2 , and circulating among the division plates as clearly shown in Fig. 4 passes down through passages a^3 on either side, thence into horizontal passages a^4 , to the cross pipe or passage a^5 which is perforated with numerous small holes from 75 which the air impinges against the bottom of the oven.

What I claim is—

Combining with the hollow cross piece b , 80 the distributer a constructed and arranged as herein set forth.

DAVID STUART.
